UNITED STATES PATENT OFFICE.

SAMUEL M. RIKER, OF CHESTER, NEW JERSEY.

BELT BUCKLE.

Application filed February 10, 1922. Serial No. 535,432.

To all whom it may concern:

Be it known that I, SAMUEL M. RIKER, a citizen of the United States, residing at Chester, in the county of Morris and State 5 of New Jersey, have invented certain new and useful Improvements in Belt Buckles; and I do hereby declare the following to be a full, clear, and exact description of the invention, such as will enable others 10 skilled in the art to which it appertains to make and use the same, reference being had to the accompanying drawings, and to characters of reference marked thereon, which form a part of this specification.

15 This invention has reference, generally, to improvements in belt buckles; and the invention relates, more particularly, to tongueless buckles or buckles provided with clamping means actuated by a pivoted cam 20 lever whereby a belt body disposed between the clamping means and the main body of the buckle is pinched or clamped so as to be held against longitudinal movement when said clamping means is operatively engaged 25 therewith.

The invention has for its principal object to provide a belt buckle with clamping means mounted upon a pivotal support so that in operation the clamping means will 30 be moved, when actuated, to tip its free biting edge toward the belt body, and at the same time so that the clamping means will automatically adjust itself operatively with different thicknesses of belt bodies which 35 may be attached to and employed with the belt buckle.

Another object of the invention is to provide in combination with the novel clamping means and mounting therefor, cooperative 40 means, in association therewith and with the cam lever device, adapted to interlock together when said cam lever is moved into operative actuating engagement with said clamping means.

45 Other objects of this invention, not at this time more particularly enumerated, will be clearly understood from the following detailed description of the same.

With the various objects of this invention in view the same consists, primarily, in the novel construction of belt buckle hereinafter set forth; and the invention consists, furthermore, in the novel arrangements and combinations of the several devices and parts, as well as in the details of the construction of the same, all of which

will be more fully described in the following specification, and then finally embodied in the claims appended thereto.

The invention is clearly illustrated in the accompanying drawings, in which:—

Figure 1 is a front face view of the novel buckle with a belt body attached thereto, and showing the free end of the belt body operatively engaged by the same; Figure 65 2 is a side or edge view of the same; Figure 3 is a rear face view of the same; Figure 4 is a longitudinal central section through the same, taken on line $\alpha-\alpha$ in said Figure 1, said view being drawn on 70 an enlarged scale, and the cam lever shown in raised or inoperative relation to the clamping means; and Figure 5 is a view similar to that shown in Figure 4, but illustrating the cam lever in actuating engage- 75 ment with the clamping means.

Similar characters of reference are employed in all of the hereinabove described views, to indicate corresponding parts.

Referring now to said drawings, the 80 novel construction of belt buckle comprises a main body consisting of a face or front plate 6 (curved longitudinally as shown if desired), side flanges 7 springing rearwardly from the longitudinal margins of said 85 face or front plate, and inwardly bent keeper flanges 8 connected with the margins of said side flanges to lie in a plane substantially parallel to and spaced rearwardly from the plane of said face or front plate 90 6. Said side flanges 7 are provided at one of their ends with rearwardly projecting perforate ears or extensions 9. Said keeper flanges 8 terminate short of said ears or extensions 9, thereby providing laterally 95 disposed shoulders 10 adjacent to said ears or extensions 9.

Pivottally connected between said ears or extensions 9 is a cam lever device, the same comprising a transverse bar 11 having journal portions 12 projecting from its respective ends, said transverse bar 11 is mounted to extend transversely between said ears or extensions 9 with its journal portions 12 pivoted in the perforations or openings of 105 said ears or extensions 9. Integrally connected with said transverse bar 11 is an outwardly extending lever arm 13, which is preferably of loop form to provide an opening 14 at its free end to receive the loop 110 15 of the attached end 16 of the belt body. Integrally connected with said bar 11 is a

cam member 17 which is preferably doubled beneath said bar to off-set the same with relation to the axis of said bar, and to provide a surface area of sufficient extent to 5 permit the formation in its operative face of a grooved or channeled seat 18 extending across the same.

Pivottally connected upon each journal portion 12 so as to swing about the axis of 10 said bar 11, the same being disposed intermediate the ends of said bar 11 and the ears or extensions 9, and so as to extend along the inner sides of said ears or extensions 9 and the side flanges 7, are supporting members or 15 arms 19 having at their inner free ends stop-lugs 20 which extend beneath said shoulders 10, so that the same lie between said face or front plate 6 and the inner ends of said keeper flanges 8, thus permitting a swinging 20 movement of said supporting members or arms 19, upward and away from said face or front plate 6, and which is limited in one direction by the engagement of said stop-lugs 20 with the inner side of said face or 25 front plate; and in the opposite direction by the engagement of said stop lugs 20 with the side flanges 7, as will be understood more particularly from an inspection of Figures 4 and 5 of the drawings. Supported upon 30 a transverse rod 21 which is fixed to and which extends between the inner free ends of said supporting members or arms 19 is one end of a clamp plate 22 which extends outwardly beneath said bar 11 and its cam 35 member 17 with its free end terminating adjacent to the adjoining lateral free edge of the face or front plate 6. The free end of said clamp plate 22 terminates in an inwardly turned biting edge portion 23. 40 Formed in the body of said clamp plate 22 is a laterally extending lock rib 24 with which the grooved or channeled seat 18 of the cam member 17 is designed to cooperate, when the said cam member is moved into actuating engagement with said clamp plate. 45 When the lever arm 13 is swung outwardly or in a counterclockwise direction, the cam member 17 is moved away from the clamp plate 22, thus freeing the latter from operative 50 clamping engagement with the free end 25 of the belt body, leaving the latter but loosely engaged by the clamping plate so that the same may be withdrawn from the buckle. 55 When fastening the belt body about the waist of the wearer, the free end 25 is inserted between the side flanges 7 to pass forwardly through the space intermediate the face or front plate 6 and the keeper flanges 60 8, and thence beneath the clamp-plate 22, the latter at the time being released from the operative engagement of the cam member 17 therewith. It will be clear that, if the belt body is of more than ordinary thickness, the 65 pivoted supporting members or arms 19 will

swing outwardly as the belt body end 25 passes beneath and presses outwardly against the cam plate, thus permitting the latter to yieldingly adjust itself to the thickness of the belt which is of advantage, since it is 70 well known that belt bodies or straps frequently vary more or less in thickness. In the novel construction of buckle here involved it will be evident that, by reason of the mounting of the clamp plate on the pivoted supporting members or arms 19, the clamping action or mechanism of the buckle is rendered initially self adjustable to the particular belt body employed therewith, which in itself is a very desirable advantage. 75 After the belt body end 25 has been passed beneath the clamp-plate, and the belt body drawn tightly into place, the lever arm 13 is swung in clockwise direction, thereby swinging the cam member 17 downwardly 80 upon the clamp-plate 22, to force the free end of the latter into clamping engagement with the belt body. The pressure of the cam-member upon the free end portion of the clamp-plate tends to press downwardly 85 said free end, and at the same time imparts a slight rearward movement to the clamp-plate which is fixed to the supporting members or arms 19, tending to thereby swing the latter on their pivotal connections until the 90 stop-lugs 20 engage the keeper flanges 8. This action results in tilting or tipping downwardly the free biting edge portion 23 of the clamp plate, to force the same into firm pinching or biting of the belt body 95 against the back of the front or face plate 6, as shown more particularly in Figure 5, all of which makes for a firm gripping clutch of the belt end 25. A further advantage of the arrangement lies in the fact that outward 100 longitudinal withdrawing strains exercised on the belt end 25, will tend to press endwise upon the free end of the clamp-plate 22, which also tends to up-tilt the free end of the pivoted supporting members or arms 19, so 105 that the biting edge 23 of the clamp plate is tilted toward the belt body, so that the same tends to offer increasing resistance to such withdrawing strains.

When the cam member is swung into operative or actuating engagement with the clamp plate 22, the seat 18 of the former will spring or snap over the rib 24 of the latter, so that a mutual interlocking of cam member and clamp plate results, which tends 110 to resist accidental releasing movement of the cam-member and its lever arm 13, all of which will be understood from an inspection, more particularly of Figure 5 of the drawings.

I am aware that some changes may be made in the various arrangements and combinations of the devices and parts, as well as in the details of the construction of the same, without departing from the scope of this in- 130

vention as set forth in the foregoing specification, and as defined in the appended claims. Hence, I do not limit my invention to the exact arrangements and combinations 5 of the various devices and parts as described in said specification, nor do I confine myself to the exact details of the construction of parts as illustrated in the accompanying drawings.

10 I claim:—

1. A belt buckle comprising a face plate, a pivoted cam member having an actuating lever arm, pivoted supporting arms arranged to swing on the axis of said cam-member, 15 means limiting the movement of said supporting arms toward and away from said face plate, and a clamp plate pivoted between the free ends of said supporting arms with its free end portion extending between said 20 cam member and said face plate, an operative movement of said cam member engaging said clamp plate to move its free end portion into gripping engagement with a belt interposed between said face-plate and said 25 clamp plate.

2. A belt buckle comprising a face plate, a pivoted cam member having an actuating lever arm, pivoted supporting arms arranged to swing on the axis of said cam member, a 30 clamp-plate carried by said supporting arms having its free end extending intermediate said cam member and said face plate, and means mutually associated with said clamp plate and said cam member to interlock the 35 same in their operated relation one to the other.

3. A belt buckle comprising a face plate, a pivoted cam member having an actuating lever arm, pivoted supporting arms, means 40 limiting the movement of said supporting arms toward and away from said face plate, and a clamp plate carried by said supporting arms with its free end portion extending between said cam member and said face 45 plate, an operative movement of said cam member engaging said clamp plate to move its free end portion into gripping engagement with a belt body interposed between said face plate and said clamp plate, and 50 means mutually associated with said clamp plate and said cam member to interlock the same in their operated relation one to the other.

4. A belt buckle comprising a face plate 55 having side flanges and keeper flanges parallel to and rearwardly spaced from said face plate, a cam member having an actuating lever arm pivotally mounted between said side flanges adjacent to one end of said face 60 plate, pivoted supporting arms arranged to swing toward and away from said face plate, said supporting arms having stop-lugs at their free ends movable between said face plate and said keeper flanges to limit the 65 swinging movement thereof, and a clamp-

plate carried by said supporting arms having its free end extending intermediate said cam member and said face-plate.

5. A belt buckle comprising a face plate 70 having side flanges and keeper flanges parallel to and rearwardly spaced from said face plate, a cam member having an actuating lever arm pivotally mounted between said side flanges adjacent to one end of said face plate, pivoted supporting arms arranged to swing 75 toward and away from said face plate, said supporting arms having stop-lugs at their free ends movable between said face plate and said keeper flanges to limit the swinging movement thereof, a clamp-plate carried by 80 said supporting arms having its free end extending intermediate said cam member and said face-plate, and means mutually associated with said clamp plate and said cam member to interlock the same in their operated 85 relation one to the other.

6. A belt buckle comprising a face plate 90 having side flanges and keeper flanges parallel to and rearwardly spaced from said face plate, a cam member having an actuating lever arm pivotally mounted between said side flanges adjacent to one end of said face plate, pivoted supporting arms arranged to swing 95 toward and away from said face plate, said supporting arms having stop-lugs at their free ends movable between said face plate and said keeper flanges to limit the swinging movement thereof, a clamp-plate carried by said supporting arms having its free end extending intermediate said cam member and 100 said face-plate, and said clamp-plate having a gripping edge at its free end directed toward said face plate.

7. A belt buckle comprising a face plate 105 having side flanges and keeper flanges parallel to and rearwardly spaced from said face plate, a cam member having an actuating lever arm pivotally mounted between said side flanges adjacent to one end of said face plate, pivoted supporting arms arranged to swing 110 toward and away from said face plate, said supporting arms having stop-lugs at their free ends movable between said face plate and said keeper flanges to limit the swinging movement thereof, a clamp-plate carried by 115 said supporting arms having its free end extending intermediate said cam member and said face plate, said clamp-plate having a gripping edge at its free end directed toward said face plate, and means mutually associated with said clamp plate and said cam member to interlock the same in their operated relation one to the other.

In testimony that I claim the invention set forth above I have hereunto set my hand 125 this 7th day of February, 1922.

SAMUEL M. RIKER.

Witness:

GEORGE D. RICHARDS.
